(57) **CLAIM**

The ornamental design for a paper towel roll core, as shown and described.

DESCRIPTION

FIG. 1 is a right perspective view of a first embodiment of a paper towel roll core according to my new and ornamental design;

FIG. 2 is a left perspective view thereof;

FIG. 3 is a front elevation view thereof, wherein the back elevation view is a mirror image of the front elevation view, and wherein the top plan and bottom plan views are identical to the front elevation view;

FIG. 4 is a cross-sectional view thereof, taken along the line 4-4 in FIG. 3;

FIG. 5 is a right side elevation view thereof;

FIG. 6 is a left side elevation view thereof;

FIG. 7 is a right perspective view of a second embodiment of a paper towel roll core according to my new and ornamental design, wherein the left perspective view is identical to that shown in FIG. 2;

FIG. 8 is a front elevation view thereof, wherein the back elevation view is a mirror image of the front elevation view, and wherein the top plan and bottom plan views are identical to the front elevation view; and

FIG. 9 is a cross-sectional view thereof, taken along the line 9-9 in FIG. 8; and,

FIG. 10 is a right side elevation view thereof, wherein the left side elevation view is identical to that shown in FIG. 6. The broken lines in FIGS. 3 and 8 are for purposes of illustrating where cross-sections of the paper towel roll core are taken and do not form part of the claimed design. The broken lines in FIGS. 4 and 9 represent boundaries and do not form part of the claimed design; the area within these broken lines is not part of the claimed design.
